UNITED STATES PATENT OFFICE.

SAMUEL EDWARD ABEY AND JAY J. HERN, OF FELLOWS, CALIFORNIA.

ELEVATOR.

1,211,999.

Specification of Letters Patent.

Patented Jan. 9, 1917.

Application filed April 28, 1916. Serial No. 94,187.

To all whom it may concern:

Be it known that we, SAMUEL EDWARD ABEY and JAY J. HERN, citizens of the United States, residing at Fellows, in the 5 county of Kern, State of California, have invented a new and useful Elevator, of which the following is a specification.

The present invention appertains to elevators for raising sucker, pump or polish 10 rods from drilled wells, and aims to provide a novel and improved device of that character.

The present device has novel means for attaching it to the sucker rod or other ele- 15 vement to be lifted, whereby the elevator is not liable to be detached accidentally, al- though it can be removed easily by hand from the rod.

It is also within the scope of the invention to provide an elevator of the nature indicated which is extremely simple, compact and inexpensive in construction, and which is thoroughly practical, reliable and efficient in use.

25 With the foregoing and other objects in view which will appear as the description proceeds, the invention resides in the combination and arrangement of parts and in the details of construction hereinafter de- 30 scribed and claimed, it being understood that changes in the precise embodiment of the invention herein disclosed can be made within the scope of what is claimed without departing from the spirit of the invention.

35 The invention is illustrated in the accompanying drawing, wherein:—Figure 1 is a plan view of the elevator, portions being broken away. Fig. 2 is a section taken on the line 2—2 of Fig. 1.

40 In carrying out the invention, there is provided a body 1 provided at diametrically opposite points with outstanding trunnions 2 adapted to be journaled in the terminals of an ordinary elevator bail (not shown), 45 and said body is also provided with a radial open slot 3 for the reception of the sucker rod or other member which is to be elevated with the body 1. The body 1 is formed at opposite sides of the slot 3 with 50 recesses 4 extending from the open end or mouth of the slot 3 to a point short of the inner end of said slot and located between the upper and lower faces of the body. The recesses 4 provide walls facing the slot 3 and 55 are provided with extensions 5 at their outer ends projecting away from one another to

those sides of the body from which the trunnions 2 project and providing walls at an angle with the aforesaid walls. The body 1 also has sockets or cavities 6 open- 60 ing into the recesses 4 adjacent their inner ends.

Mounted for swinging movements within the recesses 4 are latches 7, which are pivotally mounted upon bolts 8 or other pivot 65 elements engaged through the body 1 at the opposite sides of and adjacent to the open end of the slot 3 and extending through the recesses 4 between their ends. The latches 7 project inwardly and converge to- 70 ward one another, the inner ends of the latches being adapted to abut against the rod which fits within the slot 3 adjacent the inner end thereof. The outer ends of the latches 7 are provided with finger pieces 9 75 adjacent to the open end of the slot 3 ex- tending at obtuse angles from the latches 7 in opposite directions away from one another so as to enter the extensions 5 of the recesses. 80

The latches 7 are normally swung toward one another within the slot 3 under the influence of coiled wire expansion springs 10 confined between the body 1 and latches, said springs 10 seating in the sockets 6 and with- 85 in sockets 11 with which the latches are pro- vided.

To apply the elevator to the sucker rod, the body 1 is moved transversely so that the rod enters the slot 3, and the rod can readily 90 move past the latches 7, which are forced apart into the recesses 4 by the rod. After the rod moves to the inner end of the slot 3 past the latches, the latches will be swung behind the rod under the influence of the 95 springs 10, thus holding the elevator in place upon the rod. If the rod and elevator rotate relative to one another, this is not apt to release the latches, since the tendency of the rod in rotating against the latches to move 100 one latch into its recess tends to move the other latch out of its recess. Consequently, the latches cannot both be accidentally forced back into their recesses. When the elevator is applied to the rod, so that the 105 rod will be raised with the elevator, the elevator can be raised in the ordinary manner to carry the rod upwardly therewith. It is an easy matter to remove the elevator from the rod, since the finger pieces 9 can be 110 pressed toward one another by the thumb and one finger of the hand, which will swing

2
the latches 7 away from one another, whereby the body 1 can be moved sidewise to remove it from the rod without interference. The extensions 5 of the recesses 4 accommodate the thumb and fingers, and this facilitates the retraction of the latches from the slot 3 in withdrawing the elevator from the rod.

The present elevator is extremely simple 10 in construction, is not apt to get out of order, and fulfills its office in a thoroughly reliable and efficacious manner.

It is preferable to provide the body 1 with 15 apertures 12 extending to the faces of the body from the corners of the recesses 4, whereby sand and other extraneous matter which accumulates within said recesses can be washed out or discharged through said apertures.

20 Having thus described the invention, what is claimed as new is:

An elevator embodying a body having a radial open slot and recesses at the opposite sides of said slot between the faces of the 25 body extending from the open end of the slot to a point short of the inner end of the slot, said recesses providing walls facing the slot, said recesses having extensions projecting

away from one another at the open end of the slot for receiving the thumb and finger 30 of a hand for movement toward one another, said extensions providing walls arranged at an angle with the aforesaid walls, pivot members carried by the body within said recesses between the ends thereof, latches pivotally mounted upon said pivot members within said recesses and projecting toward the closed end of the slot, said latches having finger pieces extending at obtuse angles therefrom beyond the pivot members and 40 projecting away from one another to contact with the second mentioned walls, and expansion springs between the latches and first mentioned walls for swinging the latches toward one another and moving the finger pieces against the second mentioned walls.

In testimony that we claim the foregoing as our own, we have hereto affixed our signatures in the presence of two witnesses.

SAMUEL EDWARD AREY.
JAY J. HERN.
